US0D1099939S

(12) **United States Design Patent** (10) Patent No.: **US D1,099,939 S**
 Churchman et al. (45) Date of Patent: ** Oct. 28, 2025

(54) **DISPLAY PANEL OF A PROGRAMMED COMPUTER SYSTEM WITH A GRAPHICAL USER INTERFACE**

(71) Applicant: **Goldman Sachs & Co. LLC**, New York, NY (US)

(72) Inventors: **Christopher M. Churchman**, New York, NY (US); **Liam Kelly**, London (GB); **Martin Roberson**, London (GB)

(73) Assignee: **Goldman Sachs & Co. LLC**, New York, NY (US)

(**) Term: **15 Years**

(21) Appl. No.: **29/932,551**

(22) Filed: **Mar. 14, 2024**

(57) **CLAIM**

The ornamental design for a display panel of a programmed computer system with a graphical user interface as shown and described.

DESCRIPTION

The sole FIGURE is a front view of a display panel of a programmed computer system with a graphical user interface, showing the new design.

The outermost broken line rectangle illustrates a display screen and forms no part of the claimed design. The remaining broken lines illustrate portions of the graphical user interface that form no part of the claimed design.

1 Claim, 1 Drawing Sheet
